THREAD GUIDE FOR SEWING MACHINES

Andrew B. Clayton, Union, N. J., assignor to The Singer Manufacturing Company, Elizabeth, N. J., a corporation of New Jersey

Application March 6, 1942, Serial No. 433,539

8 Claims. (Cl. 112—218)

This invention relates to thread-guides for sewing machines and it has as a primary object to provide a tube-like thread-guide of substantial length which readily may have a thread placed therein without projecting it lengthwise therethrough and which will effectively maintain control of the thread after it has been placed in the tube.

Another object of the invention is to provide an easy threading tube-like thread-guide of simple form which may be fitted within the upper face of the work-supporting plate of a sewing machine without the necessity of performing any complicated or expensive machining operations.

A further object of the invention is to provide a slotted tube-like thread-guide which may be fitted within the upper face of the work-supporting plate of a sewing machine and into which the thread may be placed by a lateral movement of the thread, as for example by stretching the thread lengthwise of the tube and merely wiping the thread into the tube by running one finger lengthwise of the tube, in pressure contact with the upper surface thereof.

These and other objects have been attained by the provision of a flat tubular thread-guide adapted to be fitted into a plain milling cut in the upper surface of the work-supporting plate of a sewing machine, said thread-guiding tube having in its upper wall a sinuous slot through which the thread may be passed sidewise into the tube. After the thread, which passes through fixed thread-eyes at opposite ends of the tube, has been passed into the tube the oppositely directed portions of the upper wall of the tube, at opposite sides of the slot therein, overlie the thread and prevent it from being moved laterally out of the tube.

Drawing depicting a preferred embodiment of the invention has been annexed as a part of this disclosure and in such drawing:

Fig. 1 is a rear elevation, partly in section, of a portion of a two-thread chain-stitch sewing machine having the improved thread-guide embedded in the work-supporting plate thereof to guide the looper thread.

Fig. 2 is a plan view of the machine illustrated in Fig. 1 with certain parts omitted or broken away more clearly to disclose the improved thread-guide.

Fig. 3 is an enlarged cross-sectional view, taken on the line 3—3 of Fig. 2, showing the improved flat tubular thread-guide embedded in

the work-supporting plate of the sewing machine.

Fig. 4 is a plan view of a sheet metal blank from which the improved thread-guide is formed.

5 Referring more specifically to the drawing the invention is disclosed as embodied in a sewing machine comprising a frame 1 affording a horizontally disposed work-supporting plate 2, a standard 3 and an overhanging arm 4 which carries at its free end a needle-bar supporting head, not shown. Located beneath the work-supporting plate is a four-motion thread-carrying chain-stitch looper 5 which cooperates with a thread-carrying needle (not shown) in the formation of stitches, and a thread take-up mechanism T comprising a rotary take-up disk 6 and fixed thread-guides 7 and 8.

10 My improved thread-guide for leading thread t to the thread take-up T, from which it passes to the looper 5, comprises a flat metallic tube 9 which, as shown most clearly in Fig. 3, is embedded in a groove 10 milled into the upper face of the work-supporting plate 2. At the rear end of the thread-guiding tube, and recessed into 15 the plate 2, is a fixed thread eye 11 which directs the thread into the intake end of the tube. The tube is substantially rectangular in cross-section and is provided with a sinuous slot 12 through its upper wall. The tube 9 is preferably formed slightly wider than the groove 10 and because 20 of the slot 12 therein, the tube is resilient and may be slightly compressed to permit it to be forced into the groove. When the tube has been forced into the groove it is maintained therein by friction between the side walls of the tube and the vertical walls of the slot, thus eliminating the necessity of any other fastening means.

25 The thread t is adapted to be passed laterally through the slot 12 to the inside of the tube. This readily may be effected by stretching the thread lengthwise of the tube and wiping it through the slot by running one finger lengthwise of the tube in pressure contact with the upper surface thereof. When within the tube 30 and tensioned as it normally is during a sewing operation the projecting convex portions a, b, c, d, e, of the upper wall of the tube overlie the thread and prevent it from accidentally escaping through the slot 12.

35 The tube 9, with its sinuous slot 12, is preferably formed from the serpentine sheet metal blank B shown in Fig. 4. This is effected by folding the blank along imaginary longitudinal lines indicated graphically by dot-dash lines w, x, y and z. When the blank has been folded at w, x,

y and *z* into the substantially rectangular tube as shown in Fig. 3 the convex marginal portions *a*, *b*, *c*, *d*, and *e* lie adjacent to but are spaced slightly from the complementary concave marginal portions *a'*, *b'*, *c'*, *d'* and *e'*, respectively, thereby affording between them the sinuous slot 12.

After the tube 9 has been formed, the end 9^a thereof may be shaped to conform to the curved opening 2^a formed in the work-supporting plate 2 for the reception of the usual cover-plate not shown.

Having thus set forth the nature of the invention what I claim herein is:

1. In a sewing machine, the combination with a frame having an external groove, of a thread-guiding tube fitted within said groove and having a sinuous slot formed in one wall thereof for the lateral passage of a thread into the tube.

2. In a sewing machine, the combination with a work-supporting plate having an external groove in its upper surface and fixed thread-guides at the opposite ends of said groove, of a thread-guiding tube fitted within said groove, substantially flush with the face of said plate and with its opposite ends adjacent said thread-guides, said thread-guiding tube having a sinuous slot formed in the exposed wall for the lateral passage of a thread into the tube.

3. In a sewing machine, the combination with a work-supporting plate having a substantially rectangular groove formed in its upper surface, of a thread-guiding tube fitted within said groove with its upper wall substantially flush with the upper surface of said work-supporting plate, said tube being substantially rectangular in cross-section and having a sinuous slot formed in its upper wall from one end of the tube to the other for lateral passage of a thread into the tube.

4. Thread-guiding means for a sewing machine comprising a tube having in its wall a sinuous

slot extending from one end of the tube to the other for lateral passage of a thread into the tube.

5. Thread-guiding means for a sewing machine comprising a tube, having top and bottom walls and two side walls, with a sinuous slot formed in the top wall from one end of the tube to the other and extending successively from adjacent one side wall to adjacent the other side wall, 10 said slot permitting lateral passage of a thread into said tube.

6. A thread-guiding tube having a sinuous slot in one wall thereof comprising a folded blank of sheet material of serpentine shape, said sinuous slot being provided by lateral spacing of the opposite marginal edges of the folded blank.

7. A thread-guiding tube substantially rectangular in cross-section and having a sinuous slot in one wall thereof, comprising a folded blank of sheet material having transversely opposed complementary convex and concave portions which, when the blank is folded longitudinally lie adjacent to but are spaced from each other and provide between them the sinuous slot.

8. A blank for forming a folded thread-guiding tube having a sinuous slot in a wall thereof, comprising a serpentine strip of foldable sheet material, the marginal edges of which are formed as alternately convex and concave curves with the convex and concave curves of one edge transversely opposite complementary concave and convex curves of the other edge, the curvature of said blank being so proportioned with respect to the width of the blank that the blank is adapted to be folded lengthwise from end to end a plurality of times along spaced parallel straight lines between the concave curves at the opposite sides of the blank to form a slotted tube.
